UNITED STATES PATENT OFFICE.

EMILE MASLIN, OF L'ESTAQUE, FRANCE.

STEAM-BOILER.

1,009,847.

Specification of Letters Patent. Patented Nov. 28, 1911.

Application filed January 28, 1911. Serial No. 605,253.

To all whom it may concern:

Be it known that I, EMILE MASLIN, a citizen of the French Republic, residing at L'Estaque, Banlieue de Marseille, France, have invented certain new and useful Improvements in Steam-Boilers, of which the following is a specification.

One of the best means for obtaining an absolute combustion of the smoke consists in using a down-draft-furnace in which the air for combustion traverses the fuel from above. With down-draft-furnaces it is however impossible to use the ordinary grates as they would melt immediately. It has been proposed to burn the fuel upon a refractory sole but the fire-proof material is very rapidly destroyed owing to the corrosive action of the molten ashes. There is no grate known at present which is adapted to be used with down-draft-furnaces. It has further been proposed to use for down-draft furnaces a grate of infusible material composed of metal tubes in which circulates water and which is in direct communication with a steam generator. This plant is very expensive owing to the great difficulties connected with the execution of the same; it further is continually exposed to the danger of explosion for the reason of the intense vaporization produced in the tubes of the grate and of the rapid formation of scales in said tubes.

The present invention has for its purpose to avoid the aforementioned inconveniences, namely the high cost of construction and the danger of explosion. According to this invention the grates consist of metal tubes forming parts of one or of several thermic-siphons which are independent of each other.

In each of the siphons circulates a liquid, always the same, designed to transmit the heat from the grate to a boiler, the grates being cooled by the circulation of the liquid and the liquid being cooled in the boiler. The liquid circulating in the siphon can either be mercury, a suitable oil, a saline solution or simply water. This device is very economical and avoids any danger of explosion. If any of the tubes should burst, only the liquid contained in the corresponding siphon would drop into the furnace without any danger of explosion as the quantity of liquid contained in one siphon is very small. Instead of thermic-siphons metal tubes could be used which are only

partly filled with liquid, said liquid vaporizing in the parts of the tube which form the grate and condensing in the upper part of said tubes which penetrates into the boiler.

In the accompanying drawings the improved grate for down-draft-furnaces is shown.

Figure 1 is a vertical section on line A—B of Fig. 2. Fig. 2 is a plan of the grate (section on line G—H of Figs. 1—3). Fig. 3 is a vertical section on line C—D of Fig. 2. Fig. 4 shows a modification of the grate.

The grate shown in Figs. 1 to 3 is composed of six hollow grate bars coupled in pairs so as to form three separate thermic-siphons. The two bars a_1 , a_2 of the grate united by the bend a_3 (Fig. 2) form one thermic-siphon a (Figs. 1, 2, 3). Said hollow grate bars a_1 , a_2 project horizontally from the furnace and go up in a large curve to mount vertically into the water of the boiler b (Figs. 1, 3). In this boiler b the vertical extensions of the hollow grate bars a_1 , a_2 are united by the bend a_4 . The two hollow grate bars a_1 , a_2 with their extensions and bends a_3 , a_4 form an elongated hollow endless buckle. The endless tube is filled with mercury or with any other suitable liquid and forms a thermic-siphon. The tube could further be filled only partly with the liquid which in this case would vaporize in the part of the tube in the furnace to condense in the part situated in the boiler.

In order to favorize the condensation of the steam and the circulation of the condensed liquid there could be used a device like that shown in Figs. 1 to 3 consisting of a tube c_1 , c_2 connecting the two ends of a double tube c .

The boiler b can either be an independent boiler or it can simply serve as water tank for a boiler; it could be filled with any liquid which is to be heated but not to be vaporized.

As can be seen from the drawings the grate is used for a down-draft-furnace, the air traversing the fuel in vertical direction from above and the gases of combustion and the molten ashes escaping in the direction indicated by the arrow. With this arrangement an absolute combustion of the smoke is obtained with the minimum amount of air for combustion.

The grates may be of any shape: circular,

annular, rectangular and so on. The bars of the grate can be horizontal, inclined or curved according to any suitable profile.

As shown in Fig. 4 more than two bars 5 of the grate could be coupled to form a thermic siphon. The grate bars can be covered with a thin layer of refractory earth in order to facilitate the escape of the molten ashes.

10 The distance between the grate bars can be increased if between the grate and the fuel bricks or large pieces of refractory material are arranged so that the intervals between same are sufficiently large to permit 15 of the passage of the gases and of the molten ashes but not large enough to let pass the coals.

I claim:—

In combination, a down draft furnace having a grate comprising a series of independent hollow tubes spaced apart, said tubes being endless and formed with a horizontal part forming the grate and a vertical part, passing within a boiler, said boiler having a fluid to be heated therein and an auxiliary fluid circulating within the hollow tubes for transmitting heat from the furnace to the boiler. 20 25

In witness whereof I have hereunto set my hand in the presence of two witnesses. 50

EMILE MASLIN.
